UNITED STATES PATENT OFFICE.

STEPHEN PREBBLE, OF BRIXTON, ENGLAND.

SUN-BLIND FASCIA.

SPECIFICATION forming part of Letters Patent No. 740,916, dated October 6, 1903.

Application filed October 7, 1902. Serial No. 126,312. (No model.)

To all whom it may concern:

Be it known that I, STEPHEN PREBBLE, music hall director, a subject of the King of Great Britain, residing at 67 Atlantic road, 5 Brixton, in the county of Surrey, England, have invented new and useful Improvements in Sun-Blind Fasciæ, of which the following is a specification.

My invention relates to an improvement in connection with awnings for shops and other business premises; and it consists in the combination, with a roller-awning adapted to be distended in front of the window by means of hinged arms in the usual manner, of what 15 may be termed a "fascia" or "name-plate," hinged to the awning-lath and so weighted as to maintain a vertical position in all positions of the awning, so as to always present its face to public view.

20 The invention will be described with reference to the accompanying drawings, wherein—

Figure 1 represents a side sectional view of the awning as drawn down to its lowermost 25 position and as partly and fully raised, the two last-named positions being indicated in dotted lines. Fig. 2 shows the attachment of one of the fascia hinges to the awning-lath. Fig. 3 is a part rear view of the fascia, showing one of the hinge-braces. Fig. 4 is a perspective front view of an awning with the fascia applied thereto.

In the drawings, *a* is the awning, adapted to be wound on a spring-roller *a'*, mounted within 35 a boxing over the fascia of a shop-window or otherwise and attached to a lath *b*, supported by arms *c*, pivoted at *d*, so as when lowered to the position shown in full lines to support the awning over the public footway in front of the 40 shop-window in the usual manner. When thus lowered, the awning obscures the shop-front fascia, so that the trading name or style inscribed thereon cannot be seen by the passers-by, particularly when, as is usually the 45 case, the roller from which the awning is drawn is situated above the shop-front fascia. To remedy this, I provide the awning-lath itself with a fascia *e*, which may be formed either by a light metal or wooden frame carrying a panel of sheet metal or wood, or, as 50 shown, a sheet of thin metal with its margin

corrugated or beaded, as at *e'*, to stiffen the metal sheet and simulate a frame surrounding a panel adapted to bear the trading name or style or any other matter of public announcement. This fascia is loosely hung by hinges *f* at back to the lath *b*, these hinges being preferably situated at such position relatively to the height of the frame that the greater part of the fascia *e* will project upward from the lath *b* and the swinging fascia will not project so far below the awning when in the lowest position as to form an obstruction to the public. The one member *f'* of each hinge is formed with a palm *g*, adapted to be 60 screwed to the awning-lath *b*, as shown in Fig. 2, alongside the palm *c'* of the awning-supporting arm *c*, so that the invention may be readily applied to existing awnings, while the other member *f''* of the hinge is formed 65 on a substantially A-shaped frame *h*, riveted or otherwise fixed to the back of the swinging fascia *e*, these A-frames *h* not only forming a means of hinge attachment, but serving also 70 to brace and stiffen the fascia transversely, especially when it is made entirely of sheet metal. The said A-frames are made solid at the lower part, so as to assist by the distribution of their weight, supplemented by that of a metal rod *i*, of half-round section, extending 75 the whole length of the panel and inclosed within the bead at the lower edge thereof, to so balance the fascia that the part below the hinges will preponderate sufficiently to maintain the verticality of the swinging fascia in 80 all positions of the awning, as indicated by the full line and dotted positions shown.

In the raised position of the awning the attached fascia would show above the permanent fascia of the shop-window if, as is usually 85 the case, the awning-roller is situated above that fascia, and the matter inscribed on the awning-fascia may be so selected as to supplement and be read in conjunction with that appearing on the permanent fascia. 90

If the roller be situated below the permanent fascia, the fascia attached to the awning will, when the awning is raised, come in front of and take the place of a permanent fascia. 95

I claim—

1. The combination with a swinging fascia for an awning, of substantially A-shaped

frames of metal carrying hinge members, the A-frames being adapted to brace the fascia transversely and being made heavy at the lower part, a weighting-rod applied to the 5 lower edge of the fascia to coact with said heavy end of the A-frame to bring the center of gravity of the fascia below the level of the hinge-axes, as described.

2. A hinged fascia for an awning constructed of a panel, transverse braces fixed to the panel carrying hinge members set off in rear of the braces, and weighted at their lower ends, a weighting-rod attached to and extending along the lower edge of the panel, an awning-lath, and hinge members fixed to said lath for connection with the hinge members of the cross-braces, substantially as described.

3. A hinge-fascia for an awning constructed of a panel, transverse braces fixed to the 20 panel carrying hinge members, said braces being made heavy at their lower ends, an awning-lath and hinge members fixed to said lath

for connection with the hinge members of the cross-braces, as set forth.

4. A fascia extending lengthwise in a horizontal direction and edgewise in an upright position and pivotally supported at the lower edge of an awning at a point between said edge and the horizontal center of the fascia, and means whereby said fascia is caused to stand always in a predetermined position regardless of the position of the awning.

5. A hinged fascia for an awning constructed of a panel, transverse braces fixed to the panel carrying hinge members, a weighting-rod attached to and extending along the lower edge of the panel, an awning-lath, and hinge members fixed to said lath for connection with the hinge members of the cross-braces, substantially as described.

STEPHEN PREBBLE.
